CONTROL OF FUEL FEEDING DEVICES

Albert E. Baak, Minneapolis, Minn., assignor to
 Minneapolis-Honeywell Regulator Company,
 Minneapolis, Minn., a corporation of Delaware

Application January 2, 1941, Serial No. 372,783

9 Claims. (Cl. 236—46)

This invention is concerned with the control of fuel feeding devices, principally stokers and is particularly directed to improvements in automatic systems for controlling stokers in response to temperature and time and to improvements in timing apparatus adapted for use in such systems.

It is common practice to control stokers by means of a space thermostat and a timing device, the latter serving to intermittently operate the stoker for fire maintaining purposes during mild weather. The control arrangement is usually electrical, comprising circuits controlled by contact mechanism operated by the timing device and by the space thermostat.

The object of my invention is to provide an improved electrical system for controlling a stoker by a thermostat and a timer, the improvements residing in part in arrangements whereby control from the timer and adjustment of the timed operation are simplified so as to reduce the cost of manufacture and enable operators to adjust the controls with greater facility.

Another object of my invention is to provide an improved arrangement for controlling a relay by means of a timer wherein the contacts which cause energization of the relay need not be snap acting and the length of the energized period of the relay may be adjusted merely by adjusting a screw.

Another object is to provide an improved heat actuated device for producing rotary motion of a timing device.

Another object is to provide an improved heat motor for a timer having an expansible and contractible heat responsive element and arrangements whereby the element rotates a member about a shaft both when the element cools and when it heats.

Another object is to provide a device as set forth in the foregoing object wherein the heat motor is located within the rotary member.

Figure 1 is a partly diagrammatic view of a stoker control system embodying my invention showing the details of the heat motor actuated timer.

Figure 2 is a plan view of the timer cam.

Figure 3 is a view of a completely assembled control unit, embodying the timing mechanism, relay and transformers.

Figure 4 is a view of an unassembled part of the timing mechanism.

Figure 5 is a view similar to Figure 4 showing parts of the timing mechanism more completely assembled.

Figure 6 is a detail of the contacting mechanism, and

Figure 7 is a view of a modified form of heat motor.

5 Referring to Figure 1 of the drawings, numeral 10 designates a stoker which may be of any known type and which forms part of a fuel burning device which may be any of various known forms. The controls for the stoker include a relay 11 having a winding 12, the armature of which is connected to movable switch blades 13 and 14 having electrical contacts 15 and 16, the switch blades moving to the left when the winding 12 is energized bringing their 15 contacts into engagement with fixed electrical contacts 17 and 18 respectively. Numeral 21 designates a space thermostat of a known type comprising a circular bimetal element 22 to which is attached two switch blades 23 and 24 20 movable to the left by the bimetal element into engagement with fixed electrical contacts 25 and 26 respectively. The bimetal element 22 contracts upon a drop in temperature, its free end then moving in a direction to move the blades 23 and 24 to the left, the blade 24 engaging contact 26 at a predetermined temperature which may be 72°, for example, and the blade 23 engaging the contact 25 at a predetermined lower temperature which may be one or two 30 degrees lower, for example, this lower temperature may be 70°. Power for operation of the relay 11 is supplied by a stepdown transformer 29 having a primary winding 30 and a secondary winding 31, the primary winding having a greater 35 number of turns than the secondary winding. Power is supplied to the transformer 29 through wires 32 and 33 which may be connected to any suitable power source.

The relay 11 may also be controlled by a time 40 operated contacting mechanism which is designated generally by the numeral 35; the details of the time mechanism will presently be described. In connection with the timing mechanism 35, there is provided a second transformer 45 36 having a primary winding 37 and a secondary winding 38, the primary winding having the greater number of turns. Numerals 39 and 40 designate line conductors whereby power is supplied to the stoker and to the transformer 36. 50 The circuits of the stoker and the transformer 36 will presently be described.

My invention contemplates the manufacture of a unitary control device such as shown in Figure 3. This control unit or instrument includes in a 55 single casing the transformers, the relay and the

timing unit of Figure 1. In Figure 3, numeral 42 designates the casing of the control unit or device. The transformers 29 and 36 are shown suitably mounted on a panel 43 within the casing 42, which panel has brackets 44 and 45 which are disposed between suitable ears on a side wall of the casing 42 and which are fastened to the side wall of the casing 42 by bolts as shown. The relay 11 of Figure 1 may be of the hinge type, as shown in Figure 3, and is also mounted on the panel 43 on the side of the casing 42 opposite the transformers. In this type of relay the two pairs of contacts are adjacent each other and the hinged member of the relay carries bridging members which bridge the adjacent contacts. This type of relay is well known in the art and need not be described in further detail. At the upper part of the casing 42, as seen in Figure 3, adjacent the opposite sides are bracket members 46 and 47 which are secured to the bottom of the casing and which have openings through which electrical leads may be carried to the interior of the casing. Numeral 48 designates a terminal panel having a bracket 49 which is secured to the bottom of the casing 42, as shown, for holding the panel 48 in place. The panel 48 has a number of electrical terminals, as shown, formed by screws whereby the necessary wiring connections can be made. Between the transformers and the relay is mounted a generally rectangular casing 50 which houses the timing unit or mechanism of Figure 1. The casing 50 has flanges 51 and 52 which are secured to the panel 43 by screws 53 and 54. Certain adjustments for the timing mechanism are provided which may be made from the outside of the casing 50, and these adjustments will presently be described.

Referring back to Figure 1, the timing mechanism comprises a cylindrical member 57 having substantial depth, as shown, and the upper face of which is constructed so as to form a cam. The member 57 has a portion 58 at the upper part which is of smaller diameter, and it is carried on a shaft 59 which protrudes through the casing 50, as shown in Figures 1 and 3. The upper face of the member 57 has four dwells 62, 63, 64 and 65, as may be best seen on the plan view of the cam member 57 shown in Figure 2. The dwells 62 and 64 are diametrically opposed, and these dwells are of the same radial and angular extent. They are spaced from the periphery of the member 57. The dwells have a gradual rise from the face of the member 57, and they have abrupt drop-offs at 67 and 68. At the drop-offs 67 and 68 there are small depressions in the face of the cam, 69 and 70 respectively, which are of relatively small angular extent. The dwells 63 and 65 are diametrically opposed and also have a gradual rise with abrupt drop-offs at 71 and 72. The dwells 63 and 65 are similar except that the dwell 63 is of slightly greater radial extent than the dwells 62 and 64, and the dwell 65 is of slightly greater radial extent than the dwell 63, and the dwell 65 extending all the way to the periphery of the member 57. At the drop-offs 71 and 72 are depressions 73 and 74 respectively in the face of the member 57, these depressions being of the same radial extent as the dwells 63 and 65 and being of relatively short angular extent.

From the foregoing, it will be understood that the cam member 57 is wholly within the casing 50 (which is shown more or less diagrammatically in Figure 1) with the shaft 59 protruding from the casing 50 so that it may be manually rotated,

the shaft 59 having the designation "manual" adjacent it on the casing 50 as shown in Figure 3.

The cam member 57 is normally rotated in a counter-clockwise direction by a heat actuated device or heat motor designated generally at 71, which heat motor is mounted on a panel 78. The panel 78 has the same dimensions as the casing 50 including its flanges, and the panel 78 is positioned between the flanges 51 and 52 and the panel 43 with the screws 53 and 54 securing the parts in assembled relationship, the heat motor 71, as will now appear, is inside of the cam member 57 which of course, as has been pointed out above, is within the casing 50.

Referring now to the heat motor 71, numeral 79 designates an arbor carried on the panel 78 and rotatably mounted on the arbor 79 is a member 80 having a downwardly extending arm 81 and an upwardly extending arm 82. Numeral 83 designates a normally fixed arm member pivotally carried on the arbor 79 but having a screw 83a attached thereto which extends through an arcuate slot 84 in the panel 78 which screw carries a nut for fastening the arm 83 in position. The arm 83 has an ear 85, and between this ear and the arm 81 is secured a bimetal element 86 of the double helix type, as shown and described in detail in the patent of Parsons No. 2,121,259. The bimetal element 86 is formed of a strip of bimetal which is first coiled into a spiral and this spiral is then coiled into a second spiral as shown. This arrangement of the bimetal makes it possible to have a relatively large amount of bimetal arranged in a small and compact space, the amount of bimetal being sufficient to provide a relatively large amount of movement when the bimetal expands and contracts in response to temperature changes. This particular arrangement of bimetal expands and contracts in response to temperature changes along a straight line in the direction of its axis.

At the end of arm 82 is attached a finger 87 which engages the interior of the skirt formed by the cam member 57, the interior surface of the skirt being grooved or serrated as shown in Figure 1. Numeral 88 designates an angular arm pivoted on a fixed pivot 89 and also pivoted to an ear on the member 80 by means of a pivot 90. At the end of the arm 88 is a finger 91 similar to the finger 87 which also forms a pawl engaging the interior grooved surface of the skirt formed by the member 57. Numeral 95 designates a flexible blade, the lower end of which is attached to the member 82 and the upper end of which carries a contact 96, the upper end being slightly spaced from the arm 82. Attached to the upper end of blade 95 is an angular member 97 which extends through an opening in arm 82 and which has a downwardly extending projection adapted to engage the arm 82 and limit the extent to which the blade 95 may be flexed away from the arm 82. Numeral 98 designates a contact carried at the end of a contact screw 99 which extends through a bracket member 100 which is suitably secured to the panel 78. The contact screw 99 is disposed between the legs of a permanent magnet 101 which is attached to the bracket 100 by means of a clamp 102 and a screw 103. The member 97 forms an armature, and when it is brought to a position adjacent the legs of the magnet 101 it is attracted by the field of the magnet and the contacts 96 and 98 are brought together with a snap action, the blade 95 flexing away from the arm 82 which is not affected by the snap action.

With the parts of the heat motor in the posi-

tion shown in Figure 1, the element 86 is cold and is therefore in its contracted position with the legs 82 and 88 spaced relatively far apart, the contacts 96 and 98 just having been snapped into engagement. Engagement of the contacts completes a circuit for transformer 36 as follows: from line conductor 39, through wire 101, primary 31 of transformer 36, wire 106, arm 81, member 80, blade 95, contacts 96 and 98, bracket 100, and wire 108 back to line conductor 40. Completion of this circuit energizes the transformer which energizes a circuit normally extending through element 86 as follows: from secondary 38 of transformer 36 through wire 105, arm 83, ear 85, element 86, and wires 106 and 109 back to secondary 38. Energization of this circuit causes heating of the element 86 causing it to expand longitudinally of its axis, thereby rotating the arms 81 and 82 in a counter-clockwise direction about the arbor 79. The pawl 87 engages the serrations on the inner surface of the skirt of member 57 rotating it in a counter-clockwise direction. Counter-clockwise movement of the member 80 rotates the angular arm 88 in a clockwise direction about its pivot 89 so that this arm moves towards the arm 82 with the pawl 91 sliding over the serrations on the inner surface of the skirt of member 57. The contacts 96 and 98 stay in engagement with each other until the arm 82 engages the downwardly extending projection of member 97, and when this occurs, further leftward movement of arm 82 pulls the flexible blade 95 to the left so as to disengage the contacts 96 and 98 interrupting the circuit of transformer 36. When the circuit of transformer 36 is thus interrupted, winding 38 is deenergized and heating of element 86 discontinues and it begins to cool and contract. Member 80 is now rotated in a clockwise direction and angular arm 88 is now rotated in a counter-clockwise direction, the arms 82 and 88 moving away from each other. Pawl 91 now engages the serrations on the inner surface of member 57 rotating it again in a counter-clockwise direction and pawl 87 slides over the serrations. The arms 82 and 88 continue moving away from each other until contact 96 is snapped into engagement with contact 98 with the parts again in the position shown in Figure 1 wherein the circuit of transformer 36 is completed. It is to be noted that flexible blade 95 provides some freedom of relative movement between arm 82 and contact 96, that is, lost motion, so that considerable movement of arm 82 is required to effect opening and closing of contacts 96 and 98. By reason of the flexible blade 95, arms 82 and 88 can move with a smooth back and forth motion inasmuch as they are free from the effect of the snap action with which contact 96 is operated.

From the foregoing, it is to be seen that the arms 88 and 82 alternately move toward and away from each other so as to "walk" around the inner surface of the member 57 so as to rotate it substantially uniformly and continuously in a counter-clockwise direction. By loosening the screw which extends through the slot 84, the position of arm 83 may be adjusted and such adjustment of course adjusts the position of element 86 and the actuator arms 82 and 88. If arm 83 is adjusted to the right, it is to be seen that arm 82 is adjusted in a counter-clockwise direction bringing it closer to the downwardly extending projection of member 97 so that a smaller amount of lengthening of the element 86 is required to cause arm 82 to engage the downwardly extending projection of member 97 for opening the con-

tacts. On the other hand, if arm 83 is adjusted to the left, arm 82 is brought closer to the armature portion of member 97 and consequently greater lengthening of element 86 is required to cause opening of the contacts and subsequent cooling of the element 86. In other words, the length of the "steps" taken by the legs, 82 and 88 is adjusted by adjusting the position of arm 83. Thus by adjusting the position of arm 83, the length of time required for the member 57 to make one complete revolution may be adjusted. Arm 83 is so adjusted that normally the member 57 makes one complete revolution per hour.

Within the casing 50 is a cam follower arrangement and a contacting mechanism operated thereby. The outer side of casing 50 forms an adjustment or control panel, and on the inner surface of this side of the casing 50 is carried a plate to which is attached the cam follower. The control panel formed by the outer side of casing 50 may be best seen on Figure 3 and the mechanism carried on the inner surface of the control panel may best be seen on Figures 4 and 5. Figure 1 shows somewhat diagrammatically the interior of the casing 50 showing the relative positions of the cam follower and the contacting mechanism. Referring now to Figures 4 and 5, numeral 110 designates a plate having the shape shown, that is having two projecting portions 111 and 112 and a slot 113. The plate 110 is flush with the inner surface of the control panel of casing 50 as may best be seen in Figure 1. Numeral 114 designates a pin having a relatively large head, the slot 113 engaging the pin 114 so as to be guided thereby. At the end of each of legs 111 and 112 are three small spaced apertures, and cooperating with the apertures in each leg are small bosses 115 and 116 raised from the surface of the inner side of the control panel of casing 50. These bosses 115 and 116 are adapted to fit into the apertures in the legs 111 and 112 of plate 110 so as to hold the plate 110 in any one of three different positions. Numeral 119 designates a screw attached to the plate 110 which extends through a slot 120 in the control panel of casing 50. There are indicia adjacent the slot 120, as may be seen on Figure 3, the purpose of which will be explained presently. The screw 119 may be manually grasped and moved up or down in the slot 120, as seen on Figure 3, so as to move the plate 110 into any one of its three positions with the bosses 115 and 116 engaged in one of their associated apertures in the legs 111 and 112.

The plate 110 has two downwardly extending legs 122 and 123. At the lower end of these legs, there are openings, and engaged in these openings are projections at the ends of a V-shaped member 124 which forms the cam follower. The engagement of the member 124 with the legs 122 and 123 permits pivotal movement of the cam follower. The position of the cam follower with respect to the cam in the casing 50 is best shown in Figure 1. The cam follower has an extending portion 125 lying in the same plane, and this portion has two projecting portions 126 and 127 lying in a perpendicular plane (see Figure 1). The projection 126 rides on the cam member 57. The projection 127 of the cam follower 124 normally bears against an abutment 128 formed at the left end of a hinged member 129 as seen on Figure 5. The hinged member 129 may be made of Bakelite or other composition, and it has two shoulders 130 and 131 which extend through an opening in the side wall of the casing 50 ad-

jacent a pair of ears 132 and 133 extending outwardly from the side of the casing 50. The shoulders are pivoted to the ears by means of a pin 134, as shown on Figures 3 and 5, whereby the member 129 may move pivotally about the pin 134, that is in the manner of a hinge. Member 129 is normally biased about its pivot away from the control panel of casing 50 by a coiled spring as may be seen on Figure 6. The member 129 has a medial rib 135 and the abutment 128 forms part of a broader rib 136, there being rectangular recesses or depressions on opposite sides of rib 136. Numeral 137 (see Figure 6) designates a flexible contact blade, the right end of which is attached to the member 129 in the recess at one side of rib 136. At its free end, blade 137 carries electrical contacts 138 and 139. The blade 137 has an ear 140 for attaching an electrical lead thereto. Numeral 141 designates a U-shaped contact bracket which is attached to the member 129 by rivets or the like as may be best seen on Figure 5. The member 141 has a leg 142 which is flexible, the entire bracket 141 being made of flexible material. At its end the leg 142 carries a contact 143 which is adjacent and co-operable with the contact 139. The member 141 has a leg 148 which carries a contact 144 at its end which is hidden by the cam follower on Figure 5 but which may be seen on Figure 1. The contact 144 cooperates with a contact 145 on the end of a contact screw 146 (see Figure 1) which is carried at the end of a contact bracket 147 which is suitably secured to a side of the casing 50. There are rigid backing members interposed between each of the legs 142 and 148 and the member 129, and one of these may be seen at 150 on Figure 6. The member 141 has an ear 151 for attaching an electrical lead thereto.

The contact 139 at the end of blade 137 cooperates with a contact 153 (see Figures 1 and 6) carried at the end of a contact bracket 154 which is suitably secured to a side of the casing 50. Numeral 155 designates a rotatable member which is rotatable by a screw 156 which extends through the control panel of casing 50 and which is rotatable from outside of the casing. The member 155 comprises a disk portion 157, part of which is of slightly greater radius than the other part whereby shoulders are formed, as seen on Figure 4, and these shoulders cooperate with a stop 158 so as to limit rotation of the member 155 by the screw 156. The portion 157 has numbered graduations on its face from 2 to 7 and these graduations are visible through a slot 160 in the control panel of casing 50. As will be explained hereinafter the screw 156 is an adjustment for adjusting the length of time that the stoker is automatically operated by the timing mechanism for purposes of maintaining the fire. The member 155 has a circular rib 161, the edge of which forms a gradually rising surface, the rib 161 forming a cam which bears against a shoulder 162 on the contact bracket 154; thus by rotating the member 155 by means of the screw 156, the rib 161 moves the bracket 154 so as to adjust the position of contact 153. By thus adjusting the position of contact 153, the period of time that contacts 153 and 138 are kept engaged is varied, as will presently be described.

Reference is now made particularly to Figure 1 wherein the relative positions of the cam, the cam follower and the contacting mechanism within the casing 50 are shown. The projection 126 of the cam follower 124 rides on the cam 57 adjacent its periphery, and as the cam rotates, 70

one or more of the dwells on the cam lift the left end of the cam follower 124 rotating it slightly causing the projection 127 which bears against abutment 128 to move the member 129 in a counter-clockwise direction, as seen on Figure 6, that is to move the contacts 143 and 144 upwardly, as seen on Figure 1. When the screw 119 is moved downwardly in slot 120 to the end of the slot (this would be leftward movement of screw 119 as seen on Figure 1), the end of the cam follower 124 and projection 126 are very close to the edge of cam 57 so that under the circumstances the projection 126 misses the dwells 62, 63 and 64 as the cam rotates, these dwells being spaced from the edge of the cam. When the cam follower is so positioned, only the dwell 65 is effective, and under these circumstances the cam follower is actuated only once per revolution of the cam for operating the contacting mechanism. That is, there is then only one contacting operation and consequently only one timed operation of the stoker per hour as will presently appear, the screw 119 being adjacent the graduation marked 60 (the graduations adjacent slot 120 indicating minutes of time) on the control panel of casing 50. When the screw 119 is moved to a mid position in slot 120, the cam follower has its left end moved toward the center of the cam sufficiently so that projection 126 will miss the dwells 62 and 64 but both of the dwells 63 and 65 will be effective. There will now be two contacting operations per hour produced by the timing mechanism, the screw 119 being adjacent the graduation marked 30 on the control panel of casing 50. When the screw 119 is moved to the upper end of the slot 120, as seen in Figure 3, that is to the right as seen in Figure 1, the left end of cam follower 124 is moved towards the center of the cam sufficiently so that the projection 126 will now not miss any of the dwells and consequently there will be four contacting operations per hour, the screw 119 now being adjacent the graduation marked 15 on the control panel of casing 50.

The contacts 144 and 145 are normally in engagement, and when the end of the cam follower is raised by one of the gradually rising dwells causing the end of member 129 to be lifted, the leg 148 flexes, contacts 144 and 145 remaining in engagement, and contact 138 is brought into engagement with contact 153. This will happen when the projection 126 is at a predetermined position on one of the gradually rising dwells, and as the end of member 129 continues to be lifted, upward movement of leg 142 will move contact 143 into engagement with contact 139. Engagement of contacts 143 and 139 will take place when the projection 126 is at a predetermined position on one of the dwells, which position is determined by the adjustment of bracket 154 which of course is made by the screw 156 as pointed out above. As will presently appear, operation of the stoker takes place when contacts 143 and 139 are brought into engagement.

The operation of the system as a whole will now be described. Whenever the space temperature falls to 70° so as to bring both blades 23 and 24 into engagement with their associated contacts, the relay 11 is energized through the following circuit: from secondary 31 of transformer 29 through wire 170, contact 26, thermostatic blade 24, element 22, blade 23, contact 25, wire 171, wire 172, contact bracket 141, contacts 144 and 145, contact screw 146, contact bracket 147, wire 173, relay winding 12 and wire 174 back to secondary 31. Energization of winding

12 causes blades 13 and 14 to move to the left bringing their associated contacts into engagement. Engagement of contacts 15 and 17 produces a maintaining circuit for the relay 11 as follows: from secondary 31 of transformer 29 through wire 170, contact 26, blade 24, element 22, wire 175, wire 176, blade 13, contacts 15 and 17, wire 177, wire 172, contact bracket 141, contacts 144 and 145, contact screw 146, contact bracket 147, wire 173, winding 12 and wire 174 back to secondary 31. It will be seen that the maintaining circuit is independent of the thermostatic contact 25 so that after the relay has been energized, it will remain energized until the temperature rises to a value of 72° at which blade 24 disengages from contact 26. It should be noted also that both the original energizing circuit and the maintaining circuit for relay 11 extend through the contacts 144 and 145, which as pointed out above, are normally closed, and which I prefer to refer to as auxiliary contacts. When the contacts 16 and 18 are engaged a circuit for the stoker 10 is completed as follows: from line conductor 39 to wire 180, through contacts 18 and 16, blade 14, wire 181, through the stoker and wire 182 back to line conductor 40. The stoker will be kept in operation until the temperature has risen to 72° so as to cause both of the thermostatic contacts to be disengaged.

The heat motor driven mechanism operates continuously so as to keep the cam 57 constantly rotating in a counter-clockwise direction one revolution per hour. When heat requirements are relatively low so that the thermostat does not often cause operation of the stoker, the stoker must be intermittently operated by the timing mechanism to prevent the fire from going out. With the screw 119 in the mid position of slot 120 as shown on Figure 3, the projection 126 at the end of the cam follower 124 is in such a position as to make the dwells 63 and 65 effective so as to produce two automatic timed operations of the stoker per hour. Thus when the end of the cam follower is raised by one of the dwells 63 or 65, the end of member 129 will be raised and contacts 138 and 153 will first be brought into engagement. No circuits will be completed when these contacts are brought into engagement, but when the end of member 129 is further raised and contacts 139 and 143 are brought into engagement, a circuit for the relay 11 will be completed as follows: from secondary winding 31, through wire 184, contact bracket 154, contacts 153 and 138, blade 137, contacts 139 and 143, contact bracket 141, contacts 144 and 145, contact screw 146, contact bracket 147, wire 173, winding 12 and wire 174 back to secondary 31. The relay will now be energized and engagement of contacts 15 and 17 will complete a maintaining circuit for the relay as follows: from secondary winding 31, through wire 184, contact bracket 154, contacts 153 and 138, blade 137, ear 140, wire 187, wire 176, blade 13, contacts 15 and 17, wire 177, wire 172, contact bracket 141, contacts 144 and 145, contact screw 146, contact bracket 147, wire 173, winding 12 and wire 174 back to transformer secondary 31. It will be seen from the immediately foregoing, that the maintaining circuit is independent of the contacts 139 and 143. From the description previously made, it will be remembered that when the left end of member 129 is raised, contacts 153 and 138 are first brought into engagement but the relay is not energized until contacts 143 and 139 are brought into engagement. Thus as soon as the relay is ener-

gized, a maintaining circuit is formed through contacts 153 and 138 which will be relatively firmly engaged at the time, and this circuit is independent of the contacts 143 and 139 which at the time are not yet firmly engaged inasmuch as the projection 126 rises only gradually on the gradually rising cam dwells. By reason of the maintaining circuit through the firmly closed contacts, sparking is prevented at the other contacts which are not immediately firmly engaged when the relay is energized. This contacting arrangement for eliminating sparking and consequent deterioration of the contacts is a feature of my invention.

After the relay has been energized by the timing mechanism, the stoker is operated in the same manner as previously described. When the relay has been so energized, it remains energized until the projection 126 drops off the cam dwell which lifted it for operating the contacting mechanism. All of the timer contacts remain in engagement until the projection 126 drops off the cam dwell. For instance, if the cam follower was lifted by the dwell 65, when the cam has rotated sufficiently, the projection 126 will drop in to the depression 74 for opening the contacts and de-energizing the relay as will presently be described. As has previously been pointed out, the relay will be energized when the projection 126 is at a predetermined position on one of the cam dwells, for instance, on dwell 65, and this position will be determined by the adjustment of the contact bracket 154 as determined by the position of member 157. After the relay has been so energized, a predetermined number of minutes will expire during which the cam 57 will continue rotating until the cam follower, that is projection 126, drops in to a depression, for instance the depression 74. The parts are so arranged and adjusted that the said number of minutes will be the number appearing through the slot 160 of the control panel of casing 50 opposite the index marker. In other words, the number of minutes during which the relay is kept energized by the timing mechanism is determined by the adjustment of screw 156, and the desired number of minutes can be set opposite the index marker on the control panel and visible through the slot 160. When the projection 126 drops off the drop-off of dwell 65 into the depression 74, the end of member 129 is allowed to move downwardly to a position lower than normal inasmuch as the depression 74 is lower than the normal flat face of member 57. When the end of member 129 is allowed to move to the lower than normal position, the bracket 141 is moved downwardly enough to cause contacts 153 and 138 to disengage, to cause contacts 139 and 143 to disengage and also to cause disengagement of the normally closed auxiliary contacts 144 and 145. The contacts 144 and 145 remain open only for a very short time while the projection 126 is in the depression 74 (or in a similar depression). As soon as the cam has rotated sufficiently to bring the projection 126 back up on the normal flat face of the cam, the contacting mechanism is returned to its normal position as seen in Figure 1, wherein the auxiliary contacts 144 and 145 are closed. The purpose of opening the auxiliary contacts after each timed operation of the stoker is to prevent the relay remaining energized after having been initially energized by the time mechanism, that is to prevent the relay from remaining energized through the maintaining circuit of the thermostat. Thus at the expiration of a normal

timed operation, blade 24 of the thermostat 21 may be in engagement with contact 26, and while this position of the thermostat is not one calling for stoker operation, if the relay has been energized, the thermostatic maintaining circuit through contact 26 would keep the relay in energized position unless this maintaining circuit were interrupted by disengaging contacts 144 and 145. Thus after there has been a timed operation of the stoker, the relay will be positively de-energized and will only be reenergized by the thermostat if both blades of the thermostat are engaging their associated contacts. If during a timed operation of the stoker the space temperature should fall sufficiently to cause both thermostatic blades to engage their associated contacts, at the end of the timed operation the relay will be deenergized as described but will be re-energized in response to the normal thermostatic demand as soon as the projection 126 of the cam follower has passed the depression at the drop-off of the dwell to reclose the auxiliary contacts.

From the foregoing, it should now be recognized by those skilled in the art that I have provided a very compact, inexpensive and efficient control instrument embodying a timing unit occupying a minimum of space but still offering great facility, ease and simplicity of adjustment of the timing operation. The timing unit itself is driven by a heat motor which may be very cheaply made but which still provides a suitable range of adjustment of the timing and which produces uniform and accurate timing operation. The operation of the cam and cam follower, which I have provided, provides a very simple and inexpensive but yet convenient means for varying the number of timed operations during one cycle of the timer so as to adapt the instrument to use with different kinds of fuel, etc. My particular cam and contacting arrangement is such that the length of a timed operation may be very simply adjusted manually even though the arrangement does not require the use of mechanism for producing snap closure of the timing contacts. The adjustments are of such a nature that they may all be made from a single small panel lying in a single plane, the cam shaft also being so positioned that it may be manually rotated by grasping its end which extends through the control panel as described. The member 57 of course is freely rotatable in a counterclockwise direction, there being nothing to restrain its rotation in this manner. The manifold advantages and utility of my invention should be apparent to those skilled in the art from the foregoing.

Referring to Figure 7 of the drawings, I have shown a slightly modified form of heat motor for driving the timing mechanism. In Figure 7, the heat motor is mounted on a panel 78, the same as in Figure 1, and the rotary member 57 is the same as that of Figure 1. In the present embodiment, there are two bimetal elements 200 and 201 which are rigidly mounted in the position shown, being attached to brackets 202 and 203 respectively. The heating element 204 which is preferably insulated is carried on the bimetal element 200 and one end of the heating element is connected to the element 200 while the other end is connected to the source of power. At its upper end the element 200 carries an arm or finger 205 which forms a pawl engaging the serrations on the inner surface of the skirt of member 57. At its upper end, the element 201 carries a similar finger 206 forming a pawl also

engaging the inner surface of member 57. Numeral 207 designates a contact carried at the upper end of element 200, and numeral 208 designates a contact carried at the upper end of element 201. When the heating element 204 is energized to heat the bimetal elements, the element 200 warps to the left and the element 201 warps to the right. When the elements cool, they warp toward each other so as to bring the contacts 207 and 208 together.

With the parts in the position shown, the heating element 204 has been deenergized so as to allow the elements 200 and 201 to cool so that they have warped toward each other bringing the contacts 207 and 208 together. A circuit for the heating element 204 is now completed through the heating element, the bimetal element 200, contacts 207 and 208, the bimetal element 201 and the bracket 203, which is also connected to the source of power. The heating element 204 being insulated, as long as it is energized its temperature rises as the heat therein accumulates. The heat causes the bimetal elements 200 and 201 to warp away from each other, element 200 causing pawl 205 to rotate the member 57 in a counter-clockwise direction in the same manner as this member is rotated in the previous embodiment. The upper end of element 201 warps to the right, the warping of the elements of course opening the contacts 207 and 208 with the pawl 206 sliding over the serrations on the inner surface of member 57. The heat which accumulates in the heater during the time it is energized causes the bimetal elements to continue to warp to some extent after the contacts are opened. When the accumulated heat has been sufficiently dissipated so as to permit the bimetal elements to begin to cool, they warp toward each other with the pawl 206 now rotating the member 57 in a counter-clockwise direction and the pawl 205 sliding over the serrations. When the bimetal elements have cooled sufficiently, the parts again assume the position shown in Figure 7 and the cycle is repeated. It is to be seen therefore that the arms or pawls 205 and 206 "walk" around the inner surface of member 57 similarly to the operation of the previous embodiment.

The forms of my invention which I have disclosed are representative of manners in which its principles may be employed. There are other forms that it may take, and various changes and modifications may be made by those skilled in the art which fall within the spirit and scope of the invention. The invention therefore is to be limited not by my disclosure but only by the claims appended hereto.

I claim as my invention:

1. In apparatus of the character described, in combination, an automatic stoker, control means for the stoker comprising a relay, means controlling the relay comprising contacting mechanism, a timing device capable of producing uniform cycling operation of the contacting mechanism, said timing device comprising a rotatable element, means forming a cam having gradually rising dwells, a cam follower associated with said cam, said mechanism having two pairs of electrical contacts operated by said follower so arranged that the two pairs of contacts are engaged sequentially as the follower rises on a dwell, circuit means whereby the last to close of said pairs of contacts energizes said relay and whereby a maintaining circuit for said relay is formed through the other pair of contacts, manual means for adjusting at least one of said con-

tacts for varying the position of the cam follower with respect to a dwell at which the contacts close to energize the relay and to thereby vary the period of time the relay is energized, actuating means for uniformly rotating the said rotary element comprising an arm having a pawl adapted to engage the element, a second arm having a pawl adapted to engage said element, heat responsive means for actuating said arms, means whereby said heat responsive means alternately heats and cools so as to cause it to expand and contract, and means whereby said heat responsive means actuates said arms so as to cause one pawl to move the element in a given direction when the heat responsive means expands and to cause the other pawl to move the element in said given direction when the heat responsive means contracts, so that the element moves substantially uniformly and continuously in one direction.

2. In apparatus of the character described, in combination, means forming a cam having gradually rising dwells, means for driving said cam, a cam follower associated with said cam, means forming two pairs of electrical contacts operated by said follower so arranged that the two pairs of contacts are engaged sequentially as the follower rises on a dwell, manual means for adjusting one of said contacts whereby the point on a dwell at which at least one pair of contacts closes may be varied, a relay controlled by said contacts, circuit means whereby the last to close of said pairs of contacts energizes said relay and whereby a maintaining circuit for the relay is formed through the other pair of said contacts, means including a thermostat of the type having two pairs of contacts which close in sequence for controlling said relay, circuit means whereby a maintaining circuit for said relay may be formed through the first to close of said pairs of contacts of the thermostat, means including an additional pair of contacts actuatable by said cam, said last pair of contacts being normally closed and connected in circuit with said relay and said cam having a contour such that said last means opens said additional contacts for a relatively short interval of time when said follower is at a position on the cam to deenergize the relay, opening of said additional contacts interrupting the maintaining circuit of said thermostat.

3. In apparatus of the character described, in combination, means forming a circular cam having gradually rising dwells which rise from the normal surface of the cam, said dwells having abrupt drop-offs, and said cam having depressions in its normal surface of relatively small circumferential extent at the drop-offs, cam follower means associated with the cam, means forming electrical contacts operated by said cam follower means, a relay and circuit means whereby the relay may be energized by said contacts, the arrangement being such that the contacts close when the cam follower means are on a dwell and open when the cam follower means drop off a dwell, and additional normally closed contact means operated by said cam follower means for interrupting the relay circuit when the cam follower means drops into one of said depressions.

4. In apparatus of the character described, in combination, means comprising an automatic stoker, means for controlling the stoker including a relay, timing mechanism for controlling the relay comprising means forming a circular

cam having gradually rising dwells which rise from the normal surface of the cam, said dwells having abrupt drop-offs, and said cam having depressions in its normal surface of relatively small circumferential extent at the drop-offs, cam follower means associated with the cam, means forming electrical contacts operated by said cam follower means, circuit means whereby the relay may be energized by said contacts, the arrangement being such that the contacts close when the cam follower means are on a dwell and open when the cam follower means drop off a dwell, means comprising a space thermostat of the type having two pairs of contacts which close sequentially, and circuit means whereby the thermostat may also control the relay, the relay being adapted to form a maintaining circuit for itself through the first to close of the thermostatic contacts when the relay is energized, and additional normally closed contact means operated by said cam follower means for interrupting the relay circuits when the cam follower means drops into one of said depressions, said last mentioned contact means preventing the relay from remaining energized through the timing mechanism.

5. In apparatus of the character described, in combination, an automatic stoker, control means for the stoker comprising a relay, means controlling the relay comprising contacting mechanism, a timing device capable of producing uniform cycling operation of the contacting mechanism, said timing device comprising a rotatable element, actuating means for the element located therewith comprising an arm having a pawl adapted to engage said element, a second arm having a pawl adapted to engage said element, heat responsive means for actuating said arms, means whereby said heat responsive means alternately heats and cools so as to cause it to expand and contract, and means whereby said heat responsive means actuates said arms so as to cause one pawl to move the element in a given direction when the heat responsive means expands and to cause the other pawl to move the element in said given direction when the heat responsive means contracts, said timing device comprising means forming a circular cam having gradually rising dwells which rise from the normal surface of the cam, said dwells having abrupt drop-offs, and said cam having depressions in its normal surface of relatively small circumferential extent at the drop-offs, cam follower means associated with the cam, means forming electrical contacts operated by said cam follower means, circuit means whereby said relay is controlled by said electrical contacts, the arrangement being such that the contacts close when the cam follower means are on a dwell and open when the cam follower means drops off a dwell, means comprising a space thermostat of the type having two pairs of electrical contacts which close in sequence, circuit means whereby the thermostat also controls the relay, the relay being adapted to form a maintaining circuit for itself extending through the first to close of said thermostatic contacts when the relay is energized, and additional normally closed contact means operated by said cam follower means for interrupting the relay circuit when the cam follower means drops into one of said depressions, said last mentioned contact means operating to prevent the relay from remaining energized through

the thermostatic maintaining circuit when the relay has been initially energized by the timing device.

6. In apparatus of the character described, in combination, an automatic stoker, control means for the stoker comprising a relay, means controlling the relay comprising contacting mechanism, a timing device capable of producing uniform cycling operation of the contacting mechanism, said timing device comprising a rotatable element, actuating means for the element located therewithin comprising an arm having a pawl adapted to engage said element, a second element having a pawl adapted to engage said element, heat responsive means for actuating said arm, means whereby said heat responsive means alternately heats and cools so as to cause it to expand and contract, and means whereby said heat responsive means actuates said arm so as to cause one pawl to move the element in a given direction when the heat responsive means expands and to cause the other pawl to move the element in said given direction when the heat responsive means contracts, said timing device including means forming a circular cam having gradually rising dwells which rise from the normal surface of the cam, said dwells having abrupt drop-offs, and said cam having depressions in its normal surface of relatively small circumferential extent at the drop-offs, cam follower means associated with the cam, said mechanism having two pairs of electrical contacts operated by said cam follower so arranged that the two pairs of contacts are engaged sequentially as the follower rises on a dwell, circuit means whereby the last to close of said pairs of contacts energizes said relay and whereby a maintaining circuit for said relay is formed through the other pair of contacts, manual means for adjusting at least one of said contacts for varying the position of the cam follower with respect to a dwell at which the contacts close to energize the relay and to thereby vary the period of time the relay is energized, means including a space thermostat of the type having two pairs of contacts which close in sequence and circuit means whereby the thermostat also controls the relay, said relay being adapted to form a maintaining circuit through the first to close of the thermostatic contacts when the relay is energized, and additional normally closed contact means operated by said cam follower means for interrupting the relay circuit when the cam follower means drops into one of said depressions, said last mentioned contact means operating to prevent the relay from remaining energized through the thermostatic maintaining circuit when the relay has been initially energized by the timing device.

7. In a timing switch, a casing, a circular cam

within the casing and having a plurality of circularly arranged cam surfaces of substantially uniform angular extent but of different radial width, a cam follower within said casing and engaging said cam, means for causing relative rotation of said cam and cam follower, a switch comprising a pair of contacts one of which is normally fixed and the other of which is associated with said cam follower so as to be movable thereby into and out of engagement with the normally fixed contact, means for moving said cam follower radially of said cam to vary the frequency with which said cam follower and movable contact are actuated without varying the length of time the contacts are engaged, and means extending outside of said casing for adjusting the spacing of said normally fixed contact with respect to said normally movable contact to vary the length of time that said contacts are engaged.

8. In a timing switch, a casing, a circular cam within the casing and having a plurality of circularly arranged cam surfaces of substantially uniform angular extent but of different radial width, a cam follower within said casing and engaging said cam, means for causing relative rotation of said cam and cam follower, a switch associated with said cam follower and movable thereby into and out of contact making position, means extending outside of said casing for moving said cam follower radially of said cam to vary the frequency with which said cam follower and switch are actuated without varying the length of time the switch is in its contact making position, and further means extending outside of said casing to adjust the movement of said switch necessary to move it to contact making position thereby to vary the length of time that said switch is in contact making position when moved to that position by said cam follower.

9. In a timing switch, a casing, a circular cam within the casing and having a plurality of circularly arranged cam surfaces of substantially uniform angular extent but of different radial width, a cam follower within said casing and engaging said cam, means for causing relative rotation of said cam and cam follower, a switch associated with said cam follower and movable thereby into and out of contact making position, means extending outside of said casing for moving said cam follower away from and closer to the center of said cam to vary the frequency with which said cam follower and switch are actuated without varying the length of time the switch is in its contact making position, and other means for adjusting the length of time the switch is in its contact making position.

ALBERT E. BAAK.
